UNITED STATES PATENT OFFICE

171,917

LADY'S STOCKING

Abrasha Wilcher, Manchester, N. H.

Application April 23, 1952, Serial No. 19,443

Term of patent 14 years

(Cl. D47—7)

To all whom it may concern:

Be it known that I, Abrasha Wilcher, a citizen of the United States, residing at Manchester, New Hampshire, have invented a new, original, and ornamental Design for a Lady's Stocking, of which the following is a specification, reference being had to the accompanying drawing, forming a part thereof, in which:

Figure 1 of the drawing is a fragmentary perspective view of a lady's stocking as seen from the rear of the stocking looking at the heel section and sole.

Figure 2 is a perspective view looking at the side of the stocking.

The black areas and lines in the stocking indi-

cate contrasting colors. The shading indicates a slightly heavier reinforced heel section from the other portions of the stocking.

I claim:

The ornamental design for a lady's stocking, as shown and described.
